EX

MEDALLION.

No. 20,899.

Patented June 30, 1891

UNITED STATES PATENT OFFICE.

HUGH W. TAYLOR, OF AURORA, ILLINOIS.

DESIGN FOR A MEDALLION.

SPECIFICATION forming part of Design No. 20,899, dated June 30, 1891.

Application filed May 7, 1890. Serial No. 350,947. Term of patent 3½ years.

To all whom it may concern:

Be it known that I, HUGH W. TAYLOR, a citizen of the United States, residing at Aurora, in the county of Kane and State of Illinois, have invented and produced a new and useful and original Design for a Medallion or Souvenir of the World's Fair to be held at Chicago in 1892 and 1893, of which the following is a specification, reference being had to the accompanying photographs, forming part thereof.

15 The medallion or souvenir may be made of metal or other material capable of being pressed and formed by dies or graven or by other means. Its thickness is immaterial, except that a proper relation between the size 20 of the medallion and its thickness is to be observed, the same as in the case of coins and ornamental pieces. It is in the form and shape of a shield, and its edges may be smooth or milled, as may be desired. The figures and 25 illustrations upon its faces are to be bas-relief, except that the legends and dates may be intaglio, if preferred.

On the front face or surface, Fig. 1, is located in bas-relief as the central and controlling piece the portrait of Christopher Columbus, and to the right of his features is located a three-masted vessel, in bas-relief, at anchor. Spaces are left upon this face for the impression, printing, or raising, in bas- 30 relief, of the stars and stripes of the original American flag and the legends, dates, figures, &c., as shown, such as at the upper margin of the shield, on this face, the legend "Columbian Anniversary, 1492—1892," and at the 35 lower limb or margin the legend "San Salvador 1492—Chicago 1892."

On the reverse side of the medallion, Fig. 2, the central and controlling figure is that of a portrait of Queen Isabella, in bas-relief, 40 supported by the American and Spanish flags upon standards, and above her head the American eagle displayed upon the upper margin. This reverse face of the medallion has spaces for the impression, printing, or 45 raising, in bas-relief, of legends, dates, and figures, such as portions of the American flag, eight stars, portions of the stripes being obscured, and also, such as at the upper margin of the shield on the reverse face, the legend "Quadrennial Anniversary of the Discovery of America, 1492—1892," and at the lower limb or margin the legend "I am ready to pawn my jewels to defray the expenses." These dates and legends and their arrangement may be changed and varied without departing from the general character of my design.

Having thus described my invention, what I claim as new, and desire to secure by Letters Patent, is as follows:

1. In a design for a medal as herein shown and described, a shield-shaped medallion or souvenir containing upon its front face a portrait of Christopher Columbus and a vessel at anchor and space for the impression, 70 printing, or raising, in bas-relief, of the thirteen stars and stripes of the American flag and of appropriate legends, dates, and figures, and containing upon the other or obverse side the portrait of Queen Isabella and the American eagle displayed and spaces for the impression, printing, or raising, in bas-relief, of portions of the American flag and appropriate legends, dates, and figures, all substantially as shown.

2. In a design for a medal as herein shown and described, a shield-shaped medallion or souvenir containing upon its front face the portrait of Christopher Columbus and a ship at anchor and spaces for the impression, 85 printing, or raising, in bas-relief, of the thirteen stars and stripes of the American flag and appropriate legends, dates, and figures.

3. A shield-shaped medallion or souvenir containing upon its reverse side a portrait of Queen Isabella and the American eagle displayed and space for the impression, printing, or raising, in bas-relief, of portions of the American flag and appropriate legends, dates, and figures, all substantially as shown.

HUGH W. TAYLOR.
